UNITED STATES PATENT OFFICE.

JAMES S. NICHOLS, OF ATLANTA, GEORGIA.

STEAM-BOILER.

1,306,613.

Specification of Letters Patent. Patented June 10, 1919.

Application filed May 22, 1915. Serial No. 29,833.

To all whom it may concern:

Be it known that I, JAMES S. NICHOLS, a citizen of the United States, residing at Atlanta, in the county of Fulton and State of Georgia, have invented new and useful Improvements in Steam-Boilers, of which the following is a specification.

My present invention relates to improvements in steam boilers, and its primary objects are to provide a steam superheater in the fire-box thereof, and means for protecting the superheater from the direct action of the fire and for increasing the heating action upon the water of the boiler, the superheater and its protecting means utilizing to the greatest degree the heat energy from the fire and contributing to increase the steaming capacity and efficiency of the boiler.

To these and other ends, the invention consists in certain improvements, and combinations and arrangements of parts, all as will be hereinafter more fully described, the novel features being pointed out particularly in the claims at the end of the specification.

In the accompanying drawing:

Figure 1 represents a longitudinal section taken through the fire-box end of a boiler showing the present invention applied thereto.

Fig. 2 represents a horizontal section on the line 2—2 of Fig. 1.

Similar parts are designated by the same reference characters in the several views.

The present invention is applicable generally to boilers of various types, and it is more especially applicable to boilers of the locomotive type or those having an internal fire-box. The present invention is also applicable especially to locomotives or to boilers for generating superheated steam. In the present instance, the invention is shown and will be described as applied to a locomotive boiler for generating superheated steam, but it is to be understood that the invention is capable of other uses and that modification or changes in the construction and arrangement of the parts may be made within the scope of the annexed claims and which will be included thereby.

In the present instance, 1 designates the rear portion of the outer shell of a boiler of the locomotive type, and 2 represents the fire-box or combustion space which is in-

closed within the boiler, a grate 3 being located at the bottom of the fire-box for the fire, and a crown sheet 4 and rear tube sheet 5 constitute the upper and forward walls, respectively, of the fire-box. Below the rear tube sheet is formed the front water leg 6 which forms part of the water space of the boiler. The rear end of the fire-box is closed by the outer and inner shells 7 and 8, respectively, which form between them the rear water leg 9 which is also in communication with or forms part of the water space of the boiler, and a fire door 10 extends through the shells 7 and 8 and provides an opening through which fuel may be introduced into the fire-box.

The fire-box contains a steam superheater or elements or units of a steam superheater. In the construction shown, a suitable number of steam superheating elements or units in the form of headers or manifolds 11 is shown, these headers being in the present instance arranged vertically and connected at their upper ends to receive saturated steam from the boiler through the pipes 12 which pipes lead from the steam dome or any other portion of the steam space of the boiler. Each header 11 is connected by the pipes 13 to a set of steam superheating units which are contained in the flues 14 of the boiler, the saturated steam being conducted to the headers by the pipes 12 and subjected while in the headers to the superheating action of the gases contained in the fire-box. The pipes 13 leading from the headers conduct the superheated steam to the point where such steam is to be used, either directly, or through superheater units contained in the flues, as previously described.

In order to prevent overheating and consequent liability to burning or injury to the superheater when the boiler is fired and before the superheater contains steam to prevent such overheating, means is provided for flooding the superheater with water. As shown, a pipe 15 leads to the steam supply pipes 12 of the superheater, and this pipe 15 is connected preferably to receive water from the water space of the boiler by the pipe 16, a valve 17 being provided between the pipes 15 and 16 to admit water to the superheater to flood it, preparatory to firing the boiler, and to cut off the supply of water to the superheater during the normal operation of the boiler.

The present invention provides means for projecting the superheater from the intense heat of the fire, and this protecting means absorbs heat from the fire and utilizes 5 such heat in raising the temperature of the water in the boiler. The protecting means comprises a water wall through which water in the boiler circulates, this water wall being interposed between the superheater 10 and the fire to transmit heat from the fire to the water in the boiler, the water wall, however, permitting the highly heated gases from the fire-box to act upon the superheater after such gases have been reduced in temperature 15 to a suitable point which will insure efficient superheating of the steam but which will avoid overheating of or injury to the superheater.

In the present instance, the water wall or 20 superheater protecting medium comprises a unit 18 which extends continuously across the space in front of the superheater, and a suitable number of units 19 which extend across the space in front of the superheater 25 in laterally spaced relation to one another, providing passages or interstices through which the highly heated gases from the fire may circulate, but it is to be understood that the continuous element 18 may be used alone 30 or one or more rows of the units 19 may be used alone in some cases. It is preferable, however, to use both the continuous water wall 18 and the units 19 in connection with a locomotive boiler where a very intense heat 35 is developed in the fire-box by reason of the forced draft usually employed. The continuous water wall 18 and the units 19 occupy an inclined position between the fire and the superheater, and they are spaced from the 40 sides of the fire-box to provide passages 20 through which the gases may circulate around the sides of the protecting medium and thus reach the superheater indirectly, and they are also spaced from the 45 crown sheet 4 and the water leg 6 to provide passages through which the gases may circulate above and below the protecting medium and thus reach the superheater indirectly. In using two or more rows of 50 units 19, the units of one row are preferably staggered in relation to those of the adjacent row, thus providing tortuous passages between these units for the circulation of the gases, and increasing the surface af- 55 fforded by the units 19 for the absorption of heat from these gases. In using the continuous water wall 18 in connection with the units 19, it is also preferable to arrange the water wall 18 rearmost, that is to say, be- 60 tween the units 19 and the fire, thus compelling the gases to pass either around the sides or above and below this water wall 18 before reaching the units 19 or superheater, and this retarding in the outlet of the gases 65 affords ample opportunity for the heat of

such gases to be absorbed by the water and steam heating surfaces of the boiler. After the gases have passed around the sides and above and below the water wall 18, such gases may flow behind the water wall and 70 laterally through the tortuous passages between the units 19. The water wall 18 receives water from the water leg 6 by a suitable number of pipes 21 and discharges the water (the temperature of which has been 75 raised while passing through the water wall 18) through a suitable number of pipes 22 into the space above the crown sheet 4. Each unit 19 also receives water from the water leg 6 by a pipe 23 and discharges the water 80 therefrom through the pipes 24 to the space above the crown sheet 4. In order to deflect the most highly heated gases and thereby prevent their direct escape to the flues of the boiler, it is preferable to concave the water wall 18 and the units 19 toward the rear, the intensely heated gases in rising being diverted rearwardly, thus affording ample time for the absorption of 85 the heat of such gases by the boiler.

The units 19 are preferably diamond-shaped in cross-section, or substantially so, to provide interstices or gas passages of uniform width between them.

The present invention provides means 95 whereby the intensely heated gases are retarded in their escape from the fire-box, and the superheater or superheater units in the fire-box are protected from injury by such intensely heated gases, the shielding or 100 protecting medium adding to the heating efficiency of the boiler by transmitting in a large degree heat from the intensely heated gases to the water in the boiler.

I claim as my invention:

1. In a steam boiler having a fire-box, the combination of a superheater in the forward portion of the fire-box, and a water wall in the fire-box in rear of the superheater comprising a plurality of rows of transversely spaced hollow units forming interstices between them for the passage of the gases and having their tops and bottoms connected to the water space of the boiler, spaces being formed between the sides of the water wall and the adjacent sides of the fire-box for the passage of gases to the superheater.

2. In a steam boiler having a fire-box, the combination of a superheater in the forward portion of the fire-box, a water wall located toward the front of the fire-box in rear of the superheater comprising a substantially impervious hollow body connected to the water space of the boiler and extending continuously in a direction transversely of the fire-box, spaces being formed at the sides of said body for the passage of gases to the superheater, and a plurality of hollow units connected to the water space of

the boiler and arranged in front of said body and in rear of the superheater, said units forming interstices between them for the furnace gases.

5. 3. In a steam boiler having a fire-box and flues to receive gases therefrom, the combination of a steam superheater arranged in the fire-box adjacent to the entrances of said flues, and a water wall connected to the 10 water space of the boiler and providing

spaces at the sides thereof for the passage of the gases to the superheater.

In testimony whereof I have hereunto set my hand in presence of two subscribing witnesses.

JAMES S. NICHOLS.
